LASTING-MACHINE.

1,113,088.

Specification of Letters Patent.

Patented Oct. 6, 1914.

Application filed June 27, 1910. Serial No. 569,025.

To all whom it may concern:

Be it known that we, ARTHUR BATES and ROBERT H. SILVESTER, subjects of the King of England, residing at Leicester, Leicestershire, England, have invented certain Improvements in Lasting-Machines, of which the following description, in connection with the accompanying drawings, is a specification, like reference characters on the drawings indicating like parts in the several figures.

This invention relates to lasting machines, and more particularly to that type of lasting machine which is adapted to work on different parts of an upper successively, an example of which type is described in the specification of United States Letters Patent No. 584,744, dated June 15, 1897.

In prior machines of the type referred to the speed at which the machine is intended to operate is ordinarily the same for all portions of the work, notwithstanding the fact that the operator can successively present to the lasting devices certain parts of the upper more rapidly than he can present other parts thereto, during the progress of the work; and as the machine is necessarily limited to run at that speed which is required to enable the operator to last properly those parts of the upper which require the greatest amount of care it will be seen that on other parts of the upper, where he might move the shoe along and last it more rapidly, the machine is not operating to the best advantage, and hence some of the operator's time is wasted. It has been found in practice that with some grades of work there are advantages which follow from increasing the speed of a lasting machine of the class referred to at certain portions of the shoe, as for instance along the sides and at the heel, or at either of said places, and decreasing such speed at other portions, as for instance, at the toe. Such advantages are particularly noticeable in lasting shoes which are made of inferior or weak stock, as for example shoes of felt, carpet, sheepskin, or the like where the operation of the pincers could be suspended when working

along the sides of the shoe, and the stock lasted in by the presser or wiper, the speed of the machine being increased at this point in the operation and the lasting being thereby caused to proceed more rapidly until other portions of the shoe were reached at which it would be desirable to again decrease the speed of the machine. By such procedure, a considerable saving in time would be effected, and the daily output of the machine correspondingly increased.

It is an object of the present invention to improve lasting machines of this type by securing therein the results referred to, and to this end a feature of the invention comprises the provision in a lasting or like machine adapted to work on different parts of the upper successively, of speed-controlling means constructed and arranged to enable different parts of the upper to be lasted at different speeds. By the provision of such means the operator can so vary the speed of the machine that each portion of the shoe as it is presented to the lasting instrumentalities can be operated upon as rapidly as is consistent with the work to be done on that portion of the shoe and with the manipulations required of the lasting devices. The lasting devices of this type of machine include pincers which are actuated to grip each portion of the upper successively and pull it upward, and to then lay it over and upon the last. Heretofore, for lasting welted work, the machine has been provided with means for suspending the operation of the overdraw of the pincers when the heel portion of the shoe is being lasted and at the same time for actuating the tack-supplying mechanism so as to cause it to deliver shorter tacks than those supplied by it for other portions of the shoe. Such a construction, however, cannot be employed in McKay work, for in this type of shoe although it is usual to suspend the action of the pincers at certain portions, such as at the side of the shoe, the required length of tack is not to be determined solely by the part of the shoe into which it is to be driven, but rather by the thickness of the upper ma-

terials which it is to secure, it being understood that the thickness of the material to be secured varies at different parts of the shoe owing to the presence at some places of 5 bunches, or plaits.

Accordingly, the invention comprises also the provision, for a lasting or like machine adapted to work on different parts of an upper successively, of means for throwing the 10 pincer mechanism out of operation while certain portions of the shoe are being lasted without affecting the operation of the tack-supplying mechanism.

Another broad feature of this invention 15 is found in the combination with means comprising a plurality of working devices as, for example, a pincer and a tacker, or a working device having a plurality of movements as for example a pincer which has up- 20 drawing, overdrawing and plaiting movements, of provision for using less than the whole number of devices or movements and provision for changing the speed at which the device or devices are operated. In the 25 illustrated embodiment of this feature of the invention provision exists for imparting to the lasting pincer at times a plaiting movement in addition to the closing, up-drawing and overdrawing movements and 30 according to the new characteristic provision is made for changing the speed at which the machine is run so that a slower speed may be maintained when the larger number of movements are used and a higher speed 35 when the smaller number of movements are being made by the pincer. This change in speed is made, as herein shown, by means additional to that heretofore used to start and stop the plaiting movements, the ar- 40 rangement being such that while a suitable speed for lasting the toe is maintained the plaiting movements may be started and stopped as usual, but when the higher speed, which is adapted for use in lasting and tack- 45 ing the heel seat, is used, the mechanism for producing the plaiting movements is automatically thrown out of operative connec- 50 tion with the driving shaft.

An advantage of practical consequence 55 following from the use of the described pincer stopping mechanism is in the fact that the entire plaiting mechanism is rendered inactive, including the oscillating rocker which has heretofore been continu- 60 ously in motion whenever the machine was running. It will be readily understood that the entire elimination of the reciprocatory or oscillatory motion of the plaiter lever and rocker back and forth reduces materially the 65 vibration of the machine, and it is important that this be done during the time when the machine is being run at the high speed, when it is most subject to wear and tear from vibration. Also the described machine

the overdrawing movements of the pincers, whereby the pincers are rendered practically inoperative, and according to the new feature provision is made for increasing the speed of the machine when the pincer is 70 thrown out of operation and the tacker re- 75 mains in operation, and decreasing the speed again when both devices become operative. This change in speed is made simultaneously with the starting and stopping of the pincer 75 operation and each is automatically effected relatively to the other. This feature of the invention is based in part upon recognition of the fact that the more simple are the movements to be effected by the working 80 tools or the fewer are the tools that must perform their operations in coöperative relation to one another the greater are the possibilities of speeding up the machine while with increased number of working tools and 85 more complex organization in operation for producing additional movements it is reasonable to allow greater time for each cycle of the machine. Of course the speed of the described lasting machine must also be gov- 90 erned, as above fully pointed out, in accordance with the difficulties incident to the proper presentation by the operator of the different portions of the shoe to the working 95 tools, the toe portion which is to be plaited usually requiring more care than the sides and the heel portion which is not ordinarily seized by the pincers permitting the most rapid presentation of the shoe. 95

Conveniently the speed-controlling means 100 aforesaid and the pincer-controlling means are operatively connected as has been suggested so that when the speed of the machine has been accelerated to suit the requirements of the work at those portions of the shoe 105 that can be quickly lasted, the pincers shall be thrown out of operation. It is, however, within the contemplation of the invention to operate the speed-controlling means and the pincer-controlling means referred to, in- 110 dependently, one of the other.

These and other features of the invention, including the speed changing mechanism and certain details of construction and combinations of parts, will now be described in 115 connection with a preferred construction applied to a machine of the type referred to in the aforesaid Letters Patent, but it is to be understood that the invention is not to be considered as limited in its application 120 to this type of machine nor to the particular construction which is shown and described herein by way of example.

Referring to the accompanying drawings, in which the same reference characters de- 125 note similar parts throughout the several views, Figure 1 is a side elevation of a lasting machine with the present improvements applied thereto; Fig. 2 is a vertical section on the line 1—1, Fig. 1; Fig. 3 is a similar 130

section showing the parts in a different position; Fig. 4 is an elevation of a portion of the base of the machine, somewhat enlarged, showing a variable speed mechanism; Fig. 5 is a section on the line 4—4, Fig. 4; and Fig. 6 is a detail of the mechanism shown in Fig. 4, and Fig. 7 shows a modification.

The machine comprises a column 2 that supports a framework or head 4 in which is journaled the main driving shaft 6 upon which are the cams and gears which give the proper motions to the several mechanisms of the machine, including the mechanism for operating the pincers. In the base of the column 2 is journaled a countershaft 8 (Figs. 4 and 5) which is provided with a fixed pulley 10. To another part of said shaft a friction disk 12 is rigidly secured, and loosely mounted on the shaft between the fast pulley 10 and the friction disk 12 is another pulley 16 which is provided on its side adjacent the friction disk 12 with a similar friction disk 14 which may be integral with said pulley or suitably secured thereto. As is hereinafter described there is located between the adjacent faces of the friction disks 12, 14, a variable speed device. The loose pulley 16 is connected by a belt (not shown) with another pulley 18 loose upon the main driving shaft 6 in the head of the machine, and a "one position" stop and start driving clutch controlled by a pedal lever 13 pivoted in the base of the column 2 is adapted to connect the pulley 18 with the main driving shaft 6, and also to disconnect it therefrom. The connections between the "one stopping position" clutch and the pedal lever 13 comprise a vertical rod 20 pivoted at its lower end at 22 to an extension 24 from the pedal lever 13 its upper end being suitably connected with the clutch. The rod 20 also is coupled to a brake shoe 26 which is brought into contact with the pulley 18 when the clutch is actuated to disconnect said pulley from the shaft 6, but as these parts form no part of the present invention further description will be unnecessary herein.

The variable speed device, which as aforesaid is located between the friction disks 12, 14, on the counter-shaft 8, comprises a pair of idle friction wheels 28 which bear against the adjacent faces of the friction disks 12, 14, as shown in Figs. 4 and 6, one wheel on each side of the counter-shaft 8. Each of these friction wheels is rigidly secured to a short shaft 30 (see Fig. 5) journaled in the arms 31, 32, of a yoke 34 which is mounted upon the upper end of a vertical shaft 36 journaled in a bearing or bracket 38 and capable of turning therein for a purpose to be hereinafter described. Each of the arms 32 of the yokes 34 is provided with a bearing 40 in which is mounted a short vertical spindle 42 the two parts 40 and 42 forming a

telescopic coupling. On the lower end of each of the spindles 42 another bearing 44 is mounted so as to be capable of sliding on a pin 46 which is journaled in it. This pin has its axis at right angles to that of the spindle 42 as is clearly shown in Fig. 5. Each of the pins 46 is attached to one arm 48 of a frame lever 50, other arms 52 of said lever being pivotally mounted at 54 upon the bracket 38. A pin 56 located in a slot 58 in the lower end of the vertical rod 20 forms a "lost motion" connection between the pedal lever 13 and the frame lever 50 for a purpose to be hereinafter set forth. The pin 56 has springs 60 suitably connected to it which are secured to a rod 62 in the base of the machine, said springs serving to maintain, through the connections above described, the friction wheels 28 in their normal positions.

It will be clearly seen from the drawings that as the frame lever 50 is rocked about its pivot pins 54 it will, through the pins 46 and telescopic connections 40, 42, tend to vary the angular position of its friction wheels 28 in relation to the friction disks 12, 14, see Fig. 6, and consequently vary the speed of the machine.

The arrangement is such that, through the connections above described, movement of the yokes 34 aforesaid will tip the axis of rotation of each of the friction wheels 28 to the same extent but in opposite directions. Thus the paths of contact of each friction wheel with the friction disks 12, 14, will be shifted nearer to or farther from the periphery of the friction disk 12 and at the same time farther from or nearer to, respectively, the periphery of the friction disk 14 on the loose pulley 16; and as the disk 12 which is rigidly secured to the shaft 8 rotates at a constant speed it will be evident that the speed of the loose pulley 16 will depend upon the angular positions into which the friction wheels 28 are adjusted by the operator. In order that the two friction disks 12, 14, may be maintained at substantially the same distance apart irrespective of the angular positions of the friction wheels, the periphery of each wheel has a shape corresponding to that of an equatorial zone of a sphere (see Fig. 6) and the adjacent faces of the friction disk 12, 14, are recessed correspondingly.

To exert the necessary pressure between the friction disks 12, 14, and the friction wheels 28 so as to start the pulley 16 in motion the machine as herein shown is provided with a wedge-shaped member 64 (see Fig. 4) that is adapted, when the operator depresses the pedal 13 to be forced against a similar wedge-shaped surface upon a collar 66 loosely mounted upon the shaft 8 and prevented from movement lengthwise of said shaft in one direction by means of a

fixed collar 68 and in the other direction by the wedge-shaped member 64. A thrust collar with ball bearings 70 may be interposed between the two collars to lessen the friction between said parts. The opposite face of the wedge-shaped member 64 abuts against the boss 72 of the loose pulley 16, a collar similar to and performing the same function as the collar 70 being interposed between the boss 72 and the said face.

10 A toggle joint 74, 76, pivotally connects the extension 78 of the pedal 13 with the lower end of the wedge-shaped member 64 and a spring 80 tends to maintain the toggle 15 in its normal or straightened condition, the extent to which the toggle is straightened being preferably determined by a lug 82 of the member 74 contacting with a lug 84 of the member 76 as shown in Fig. 4. If desired, one of said lugs could be provided with an adjusting screw made to engage the other lug so that the extent to which the toggle is straightened could be varied. The spring 80 also serves to maintain the wedge-shaped member 64 in the operative position 25 while the operator is working the pedal 13 to vary the speed of the machine.

30 The lugs 82, 84, are so arranged that the toggle 74, 76, is bent slightly and when the friction disks 12, 14, are forced by movement of the wedge-shaped member 64 into engagement with the friction wheels 28 the toggle will "break," thus permitting the pedal lever 13 to be depressed farther to 35 alter the speed of the loose pulley 16 by adjustment of the angular position of the friction wheels 28. In this connection it will be noted that the "breaking" of the toggle 74, 76, indicates to the operator that a further 40 depression of the pedal 13 will vary the speed of the machine.

45 To enable the pedal to be depressed for raising the brake 26 and setting the wedge 64 to start the machine and cause it to run without affecting the speed changing mechanism, there is provided a "lost motion" connection, 56, 58, (see Fig. 5) as hereinbefore mentioned in the chain of connections between the friction wheels 28 and the foot 50 pedal 13. Alternatively to the wedge arrangement for throwing the friction gear into operation, the yokes 34 carrying the friction wheels, when the pedal 13 is released, may be moved by any suitable arrangement through an angle on their pivots 55 sufficiently great to shift the peripheries of the friction wheels beyond or away from the recessed portions of the driving and driven friction disks with which they normally engage. Conversely, depression of the pedal 60 will shift the wheels first into engagement with the friction disks and then vary the speed or the ratio of the gear. When this method of throwing the friction gear into 65 action is utilized, the driving and driven

friction disks are preferably given a limited amount of play axially, and a suitable spring or yielding thrust bearing or device is preferably provided that holds them yieldingly toward each other and causes the necessary 70 friction between them and the friction wheels. Furthermore the friction faces of the disks may be so shaped, at the portions where the friction wheels first engage, as to form a slight angle with the direction of 75 motion of the peripheries of the said wheels and thus constitute a lead to enable them readily to enter into full engagement.

80 The lasting and tacking mechanisms include, as set forth more at length in said prior Letters Patent, the pincers 130 which are suspended from the front end of the updraw lever 132. This lever is fulcrumed at 133 and at its rear end it is connected through spring 134 to the cam 135, Figs. 1 85 and 7. The pincers are closed by the downward movement of a rod 136 effected by an arm 137 of a rock shaft 138 the other arm 139 of which rests on the periphery of a cam block 86. This cam block has a track 90 in its front side from which is actuated a lever, not shown, here to oscillate a sleeve shaft 140 and rocker 142 to give plaiting movements to the pincers when set to do so by the bell crank 143 and knee lever 145 95 all as fully explained in said patent from which it will be learned that the plaiting movements are started and stopped by manipulation of the knee lever additional to the other, normal, movements of the pincers. The pincers are also moved outwardly from the machine, see dotted lines Fig. 7, to produce the "overdraw" by means of a spring-operated thrust rod 88 of which the movements are controlled by a face 100 formed on the rear side of the cam block and engaging a roll 87 on the pincer thrust rod. In the preferred construction herein described means are provided for suspending the operation of the pincer by disconnecting the cam 86 from which are derived the pincer closing, overdrawing and plaiting movements. While the plaiting movement of the pincers is susceptible of independent control by the knee lever 145 that movement, with the overdrawing and closing movements, is started and stopped by the cam 110 115 86 while the updraw movement as herein shown is continuous at all times.

120 In a contemplated use of the machine the machine will be run at its starting or minimum speed while the toe portion of the upper is being lasted over and plaited into place upon the shoe bottom. When the toe of the shoe has been completed the plaiting mechanism is thrown out of operation by the knee lever 145 and when the sides are reached, or before if desired, the speed may be increased to the maximum at which the operator can properly present the shoe to 125 130

the pincer and the tacker. When the heel portion of the shoe is reached where no pulling by the pincers is required, or when any portion of the side is reached which can be properly lasted by the reciprocating wiper and tacker without the aid of the pincers, a further depression of the foot treadle operates the clutch to be described to throw out of operation the pincer cam 86 and simultaneously to increase the speed at which is driven the actuating mechanism, including the gripper updrawing cam and the tacker operating cams. By this arrangement one of the working movements 10 which can be imparted to the pincers, that is, the plaiting movement, can be suspended and resumed at the will of the operator and, at the option of the operator, the speed increased at which the remaining movements 15 are effected. Also the pincers can be thrown wholly out of operation and the speed of another working device, which is the tacker, and of the entire actuating mechanism of the machine will be automatically increased. 20 To provide for such uses of the machine in which the invention is illustrated, and other uses which may be found desirable, the cam 86 is connected to the shaft 6 of the machine by a clutch which is controlled 25 from the pedal 13 by means of the vertical rod 20 to which is adjustably and detachably connected by a clamping screw 91 a rod 90 (see Fig. 1) that is in turn connected to a lever 92 pivoted at 94 upon the 30 head of the machine. The free end of this lever has a cam face 96 upon it, which on depression of the pedal 13 is adapted to be forced into contact with a plunger 98 arranged to have a sliding movement limited 35 by means of a pin and slot connection 97, 99, in a bearing 100 arranged in the head of the machine. A spring 102, of which one end abuts against a shoulder 104 on the inside of the bearing 100 and the other end 40 against a collar on the plunger 98 (see Fig. 1), maintains the said plunger always in contact with the end of the lever 92. Connected to the forward end of the plunger 98 is a rod 106 that is coupled to a 45 lever 108 that forms part of the clutch-operating mechanism, hereinafter described, which renders the overdraw movement of the pincers inoperative while the side or heel portions of the shoe are being lasted. 50 The cam 86 is loosely mounted upon the main driving shaft 6. A pawl 110 pivoted at 112 upon the cam 86 has a projection 114 that is adapted under the action of a spring 116 to engage a recess 118 formed in a collar 55 117 rigidly secured to the shaft 6. With this construction it is obvious that when the projection 114 of the pawl 110 engages the recess 118 in the collar 117 that the cam member 86 will be rotated to operate the 60 pincers for the overdraw movement, and

that when the projection 114 is disengaged from the recess the cam 86 will be disconnected from the shaft 6 and may be arrested to stop the grippers in a predetermined position as hereinafter described.

The means for causing the pawl 110 to be disengaged from the recess in the collar 117 comprises the lever 108 above mentioned which is pivoted at 109 upon a pin that extends transversely of the machine. The lever is provided at its upper end with a wedge-shaped portion 120 shown by dotted lines in Figs. 2 and 3. This wedge-shaped portion is adapted, when it is desired to suspend the overdraw movement of the pincers, to be introduced from the front by movement of the lever 108 into a position in which it will engage a projection 121 of the pawl 110 during the next rotation of the cam to withdraw the pawl from the recess 118 in the 75 collar 117. After the pawl has been disconnected from the collar 117, further rotation of the cam 86 is prevented by the projection 121 coming into contact with a portion 122 on the upper end of the lever 108.

The rod 106 that connects the lever 108 with the plunger 98 is provided with a pin and slot connection 124, and a spring 126 is interposed between the end of the rod 106 and the bottom of a socket in the plunger 98. In the event of the operator, through the connections described, moving the lever 108 at a time when the pawl 110 has just passed the position in which it is capable of being withdrawn from the recess in the collar 117, this pin and slot connection will permit the lever 108 to pause until the pawl has moved from engagement with it whereupon the spring 126, which will have been compressed by the action of the operator, will expand 100 and complete the movement of the lever 108 into the position in which it is in readiness to withdraw the pawl from the recess in the collar 117.

It will be understood that mechanism 110 such as herein described, or any equivalent mechanism, for suspending the operation of the pincers does not affect the operation of the thick presser or wiper device 148 described and shown in the Letters Patent 115 above referred to. When the pincers are thrown out of operation on those portions of a shoe where the operator finds it to be undesirable to pull the upper, therefore, the lasting operation is performed by the thick 120 presser which pushes the upstanding upper over upon the innersole, to which it is secured by the tacks or other fastenings as the work progresses.

The operation of the machine is as follows:—The parts being in the position shown in Figs. 1 and 4, the operator depresses the pedal 13 thus raising the rod 20 and removing the brake shoe 26 from the pulley 18 and by means of the wedge-shaped 130

portion 64 forcing the friction disks 12, 14, into contact with the friction wheels 28, so that the machine is started. When the operator desires to increase the speed of the 5 machine he depresses the pedal 13 further and this causes the lower wall of the slot in the rod 20 to engage and lift the pin 56 and move the frame lever 50 about its pivots 54. This movement of the frame lever through 10 the telescopic connections hereinbefore described will alter the angular position of the friction wheels 28 in relation to the friction disks 12, 14, and thus vary the speed of the machine. When the heel or other portion 15 of the shoe is to be lasted without the use of the pincers the operator still further depresses the pedal 13 and this, through the rod 20, brings the cam face 96 on the lever into contact with the plunger 98 thereby 20 moving the rod 106 and the lever 108 toward the left in Fig. 1 so that the projection 114 of the pawl 110 will be brought by the rotation of the cam 86 (in the direction indicated by the arrow in Figs. 2 and 3) into engagement 25 with the wedge-shaped part 120 on the lever 108 and be withdrawn from the recess 118. The cam 86 is now disconnected from the shaft 6 and is brought to rest by the engagement of the part 122 on the lever 108 30 with the projection 121 on the pawl 110, thus suspending the overdraw movement of the pincers.

At any time in the toe or side lasting operation the workman can force down the 35 pedal to cause the tacker to wipe the upper over and insert a plurality of tacks in rapid succession without the use of the pincers. This is particularly desirable in lasting the sides of the shoe where it often occurs that a 40 plurality of operations of the wiper and tacker to each pulling operation of pincers can be employed advantageously. By adjustment of the connection 91 the time at which the throwout will occur can be 45 changed with relation to the progressive increase of the speed which is effected by the depression of pedal 13. If it should be desired to employ the high speed with the pincers in operation the clamp 91 can be 50 loosened to disconnect the clutch from the pedal 13. In making welt shoes it is customary to fasten the plaited toe portion of the upper by a binding wire and in this work the tack inserting operation is not 55 needed. By an obvious extension of this invention a throwout clutch may be connected with an element of the tacker actuating mechanism, as for example the cam 150 which operates the tack block 147 and as 60 sociated devices through the lever 152 and slide 154, to discontinue the upper fastening operation by tacks while the slow speed employed for plaiting is in use and to resume the tacking operation automatically when 65 the higher speed suited for side lasting is

attained. Obviously the plaiting mechanism may also be controlled with the speed changing control by a connection from the rod 144 or the like to the pedal rod 20 instead of being controlled by the separate knee lever as 70 in the prior patent mentioned.

Instead of the mechanism herein shown and described by way of example for suspending the operation of the pincers any other suitable means for producing this result 75 may be employed. As shown in Fig. 7 for example, the roll 87 on the pincer thrust-rod 88 that is operated by the cam 86 instead of being mounted directly upon the thrust rod could be carried upon a sleeve 80 on the rod, and there may be provided a detent 160 pivoted upon a block secured to the rod and adapted to engage the sleeve. When the detent is engaged with the sleeve 85 the pincer thrust rod will be actuated by the coöperation of its spring and the cam 86 to effect the overdraw of the upper but when the detent is disengaged from the sleeve by mechanism hereinafter described the spring of the thrust rod will move the 90 rod forward and hold the pincers out of engagement with the upper. At this time a light spring 162 keeps the roll in engagement with the cam and the said sleeve is moved idly upon the thrust rod so that the 95 detent when released to reengage the sleeve shall reengage it at the proper time in the cycle of operations of the machine. The mechanism for disengaging the detent from the sleeve on the thrust rod may comprise 100 the rod 90 and the clamp 91 that is adjustably mounted on the rod 20 which couples the pedal lever 13 with the clutch for the pulley on the main driving shaft. By this arrangement when the operator depresses 105 the pedal lever the extent that is necessary to give the speed that is desirable for the lasting of a portion of the shoe which does not require the pull of the pincers, the detent 160 will be disengaged from the sleeve 110 on the thrust rod by the connections described and the operation of the pincers will be suspended.

It is obvious that instead of the mechanisms herein shown and described for suspending the operation of the pincers when the speed is changed any other suitable mechanism for producing this result may be employed, for example the cam that produces the updraw movement of the pincers 115 may be provided with devices such for example as shown in British Patent No. 11131/03 and connected with the speed changing mechanism for disconnecting the cam from the main driving shaft of the machine or both the updraw cam and the overdraw cam may be provided with such devices. Moreover in place of the particular construction herein set forth any other 120 suitable speed-controlling means may be em- 125 130

ployed for varying the speed of operations of the machine such for example as that shown in Fig. 7, and in a broad aspect of this invention the speed-controlling and pincer-controlling means might be entirely independent so that each may be operated without affecting the other.

In the construction of speed controlling means shown in Fig. 7, approximately 10 spherical faced idle friction wheels 164, 166, corresponding to the friction wheels 28 of the first construction, instead of bearing against separate friction disks, are interposed between the fixed pulley 10 and the 15 loose pulley 16 and bear respectively against adjacent annular flanges or rims 168, 170 on the said pulleys 10 and 16. The wheels 164, 166 have a peripheral contour substantially like that of the wheels 28 of the first 20 construction and the flanges or rims 168, 170, are, like the friction disks 12, 14, of the first construction, recessed correspondingly. The idle friction wheels 164, 166 are respectively pivoted at 172, 174 in suitably supported rocker frames 176, 178, moved to change the angular plane of the 25 wheels 164, 166 by crank arms 180 fixed to extensions of the frames 176, 178, the variation in the paths of contact of the wheels 30 164, 166 with the flanges 168, 170 being indicated by and along the lines of the broken line arcs 179. Turning movement of the crank arms 180, operating through the rocker frames 176, 178 to change the angular 35 plane of the idle friction wheels 164, 166 and thus to vary the paths of contact of each of said wheels 164, 166 with the flanges 168, 170 on the pulleys 10 and 16, operates to impart varying speeds to the 40 loose pulley 16 from the constant speed pulley 10 and thus to vary the speed of the machine in substantially the same manner as in the first construction. For operating the crank arms 180, the said crank arms 45 are connected by links 182, 184 to an arm 186 fixed to the rock shaft 188 about which the pedal 13 turns. As in the first construction, there is provided a lost motion connection at 190, arranged so that the initial 50 movement of the pedal 13 to start the machine will not alter the angular position of the idle friction wheels 164, 166, the lost motion connection 190 not giving out to its full extent until after the pedal 13 has been 55 depressed sufficiently to start the machine. Thereafter further depression of the said pedal operates through the connecting rods 182, 184 and crank arms 180 to move the friction wheel carrying rocker frames 176, 60 178 so as to turn the friction wheels 164, 166 to accelerate gradually the speed of the machine. The wedge 64 of the first construction is employed to put upon the pulley 16 the pressure required to render the friction 65 wheels 164, 166 effective and a spring 192,

operating substantially like the spring 80 of the first construction, serves to keep the wedge 64 in operative position while the operator is manipulating the pedal 13 to vary the speed of the machine.

Having described our invention what we claim as new and desire to secure by Letters Patent of the United States is:

1. A machine of the class described having, in combination, means for working an upper over a last, devices for controlling the speed of said means and connections serving to change the character of the operation effected by said upper over-working means on the shoe concurrently with the change in speed.

2. A machine of the class described having, in combination, means for operating upon successive parts of an upper to work it over a last and devices for varying the speed of such means and serving also to vary the character of their operation on different parts of the shoe.

3. A machine of the class described having, in combination, lasting means including pincers for working successive parts of an upper over a last, speed - controlling means, and connections therefrom to the pincers operating to vary the paths of said pincers as the speed is changed for operating on different parts of the shoe.

4. A machine of the class described having, in combination, means for working an upper over a last, a variable speed-gear for said means, means for manually controlling the operation of said speed-gear, and means for changing the character of the operation effected by said overworking means on the shoe, said means acting automatically after the speed controlling means has been operated.

5. A machine of the class described having, in combination, lasting mechanism, means for controlling the speed of said mechanism, means for suspending the operation of said mechanism, and a single device to operate both of said means.

6. A machine of the class described having, in combination, a tacker, lasting mechanism, and means for varying the speed of said lasting mechanism and for thereafter suspending the operation of said lasting mechanism while the tacker continues in operation.

7. A machine of the class described having, in combination, pincers and actuating mechanism therefor, and means for accelerating the operation of said pincers and, by continued actuation in the same direction, for thereafter suspending the operation of said pincers.

8. A machine of the class described having, in combination, lasting devices including pincers and actuating mechanism for said devices constructed to work successive

portions of an upper over a last, and means for accelerating the operation of said devices and for thereafter suspending the operation of the pincers while the other lasting devices continue in operation.

9. A machine of the class described having, in combination, pincers, a shaft, a cam carried by the shaft and arranged to control the overdraw movement, and means arranged for manual operation to disconnect said cam and shaft.

10. A machine of the class described having, in combination, devices for working successive portions of an upper over a last, including pincers, actuating mechanism for said devices including a variable speed-gear, and controlling means for said speed-gear arranged to accelerate the operation of said devices and by continued movement in the same direction thereafter to render the pincers inoperative.

11. A machine of the class described having, in combination, pincers and actuating means therefor for working successive parts of an upper over a last, mechanism for securing the upper in overworked position, speed controlling means, and means for suspending the operation of said pincers automatically when the speed of the machine has been raised to a predetermined point but without affecting the operation of said securing mechanism.

12. A machine of the class described having, in combination, pincers and actuating mechanism therefor for working successive parts of an upper over a last, means for controlling the speed of said mechanism, and means for suspending the operation of the pincers when the speed of said mechanism exceeds a predetermined limit.

13. A machine of the class described having, in combination, lasting devices, actuating mechanism therefor including a driving shaft, a one-revolution clutch for connecting said shaft with a source of power, a variable speed-gear having connection with said shaft, and a controlling device arranged to first actuate said clutch to start the machine and thereafter to actuate said speed-gear to vary the speed of said lasting devices.

14. In a lasting machine, lasting devices having side lasting movements and different heel seat lasting movements, and variable speed operating mechanism for said lasting devices arranged to change the lasting movements coincidentally with a change in the speed at which they are operated.

15. In a lasting machine of the step-by-step type, the combination with a gripper adapted to seize and stretch an upper over a shoe bottom into position to be tacked and a tacker and wiper for laying the upper upon the shoe bottom and fastening it, of operating mechanism and a controlling

treadle arranged to actuate the gripper and the tacker and wiper in time relation at a relatively slow speed and to render the gripper inoperative and last the upper by the tacker and wiper alone at a higher speed.

16. A shoe making machine having, in combination, a plurality of working devices arranged for use in coöperation with one another, actuating mechanism therefor, means permitting discontinuance of the use of one of said devices at times without interrupting the use of another of said devices, and connected mechanism for changing the speed of the device or devices which remain in operation concurrently with discontinuance of use of one of said devices.

17. A shoe making machine having, in combination, a plurality of devices for working on a shoe, actuating mechanism therefor, means permitting discontinuance of the use of one of said devices at times without interrupting the use of another of said devices, and a single controller operating to change the speed of the actuating mechanism when one of said devices is thrown into or out of operation.

18. A machine of the class described having, in combination, a working device, actuating mechanism for imparting a plurality of operating movements to the device during the same cycle of the machine, means for suspending one of such operating movements while the others are continued, and operatively connected mechanism for increasing the speed of the actuating mechanism simultaneously with such suspension.

19. A machine of the class described having, in combination, a working device, actuating mechanism for imparting a plurality of operating movements to the device, for suspending one of such operating movements while the others are continued, and means for increasing the speed of the machine when such suspension occurs and decreasing the speed when the suspended movement is resumed.

20. A shoe making machine having, in combination, a plurality of devices for working in coöperation upon a shoe, actuating mechanism therefor, and connected means for rendering one of said devices inoperative and simultaneously changing the speed at which another device is driven.

21. A machine of the class described having, in combination, a working device, actuating mechanism for imparting a plurality of operating movements to the device, and connected means for suspending one of said movements and automatically increasing the speed at which the actuating mechanism is driven.

22. A machine of the class described having, in combination, a pincer, a tacker, actuating mechanism, means by which one

of said devices may be rendered operative or inoperative, and one controlling mechanism for said devices including means by which the speed of the actuating mechanism may be varied according to the device or devices which are in operation.

23. A machine of the class described having, in combination, lasting devices comprising a pincer, and a tacker, operating mechanism for said devices, means by which one of said devices may be rendered operative or inoperative, means for changing the speed of said operating mechanism, and one controller for both said means operating to effect a different speed of the operating mechanism when one of said devices is inoperative.

24. A machine of the class described having, in combination, a pincher, a tacker, means by which one of said devices may be rendered operative or inoperative, actuating mechanism, means to change the speed of the machine, and connections between said two means operating to cause a device to be automatically rendered operative or inoperative whenever a certain change in the speed of the machine is effected.

25. A machine of the class described having, in combination, a pincer, means for effecting updraw movements of the pincer, means for effecting overdraw movements of the pincer, and actuating mechanism for said two means, said machine having one controlling means for effecting discontinuance of one of said movements and for changing the speed of the actuating mechanism when such discontinuance is effected.

26. A machine of the class described having, in combination, a pincer, means for imparting normal pulling movements to the pincer, means adapted to be rendered operative or inoperative for imparting additional plaiting movements to the pincer, and connected devices for simultaneously controlling said last named means and the speed of the machine.

27. A machine of the class described having, in combination, a pincer, a cam shaft, an updraw cam, a plaiter cam, connections from said cams to the pincer, and means for discontinuing the operation effected by the plaiter cam and simultaneously increasing the speed at which the cam shaft is driven.

28. A machine of the class described having, in combination, an operating device, driving mechanism including means to impart to said device a plurality of different movements, and one controlling mechanism by which one of said movements may be suspended and resumed, and the speed of the driving mechanism may be changed simultaneously with such suspension or resumption of the movement of the operating device.

29. A machine of the class described hav-

ing, in combination, a working device, means for imparting to said device a plurality of different movements in each cycle of the machine's operation, and means for suspending and resuming one of said movements while another continues, and for accelerating a continuing movement.

30. A machine of the class described having, in combination, a pincer, a tacker, actuating mechanism for the pincer and the tacker, and means to cause suspension of the operation of the pincer when acceleration of the operation of the tacker is effected.

31. A machine of the class described having, in combination, a pincer, a tacker, actuating mechanism for the pincer and the tacker, and connected means for controlling the operation of one of said devices and changing the speed at which the actuating mechanism drives the other of said devices.

32. A shoe making machine having, in combination, two working tools adapted to coöperate together upon the shoe at times and one of said tools being capable of use on the shoe without the other, actuating mechanism including operating connections to said two tools, and one means for controlling the operativeness of one tool and changing the speed at which the other tool is driven.

33. A shoe making machine having, in combination, a working tool, a second working tool, actuating means for said two tools, means for rendering the second tool operative or inoperative, and means by which the speed of the first tool must be changed whenever the second tool is started and stopped.

34. A shoe making machine having, in combination, a plurality of working devices, means for rendering one of said devices operative at some times and idle at other times, and means controlled by said first mentioned means for governing the speed of the machine appropriately to the devices that are in use.

35. A machine of the class described having, in combination, a pincer, a tacker and wiper, actuating mechanism for said parts including the pincer closing, overdrawing and plaiting cam 86, and means under control of the operator to discontinue the movements effected by said cam while the tacker and wiper continue to be operated.

36. A machine of the class described having, in combination, a pincer, a tacker, actuating mechanism for said parts, and operatively connected means under control of the operator for varying the speed at which said parts are driven and for discontinuing the operation of one of said parts upon the work.

37. A shoe making machine having, in combination, a pincer, a tacker, actuating mechanism for said parts including a speed controlling device and connections therefrom

- to throw one of said parts into or out of operation in changing from one speed to another speed.
38. A machine of the class described having, in combination, a pincer, a tacker, actuating mechanism for said parts including a speed controlling device capable of varying the speed at which the pincers and tacker are operated together and connections therefrom to discontinue the operation of one of said parts when a certain change in speed is made.
39. A machine of the class described having, in combination, pincers, other lasting devices, pincer controlling means and speed controlling means operatively connected to cause the pincers to be thrown out of operation by accelerating the speed of the machine.
40. A machine of the class described having, in combination, a pincer, a tacker, actuating mechanism for said parts, a speed varying device and controlling means to enable a plurality of speeds to be obtained for said devices when they are working together and to render one of said devices ineffective and permit a different speed to be obtained for the other device.
41. A machine of the class described having, in combination, a pincer, a tacker, actuating mechanism, a controlling member, and connections from the controlling member to said actuating mechanism adapted to be operated upon movement of the controlling member to suspend one or more pulling movements of the pincer and also adapted to be operated while such suspension continues to cause the tacker to insert tacks at an increased speed.
42. A shoe making machine having, in combination, two working devices adapted for operating together on a shoe, actuating mechanism therefor, and one controlling means by which the operation of one of said working devices may be suspended during one or more cycles of the machine and the other device to operate at a different speed from the normal one during such suspension.
43. A machine of the class described having, in combination, two tools adapted to operate upon the same portion of the work, actuating mechanism therefor, speed changing means, and controlling means for determining whether one or both of said tools shall work and producing an accompanying change in the speed of the actuating mechanism.
44. A machine of the class described having, in combination, a pincer to pull an upper, a tacker to fasten the upper, actuating means, speed changing means, and means for automatically discontinuing one of said operations while the machine is being run at a predetermined speed.
45. A machine of the class described having, in combination, a pincer to pull an upper, a tacker to fasten the upper, actuating means, speed changing means, and means connected with the speed changing means for actuation by force applied at a single point adapted to be rendered operative or inoperative for discontinuing one of said operations on the upper while the speed is being changed.
46. A machine of the class described having, in combination, a pincer, a tacker, actuating mechanism therefor, and means under control of the operator for progressively increasing or decreasing the speed at which the said devices are driven and means operating automatically to change the operation of one of said devices when a predetermined change in speed has been effected.
47. A machine of the class described having, in combination, a pincer, a tacker, actuating mechanism therefor, means under control of the operator for progressively varying the speed at which the devices are driven, and means adjustable to cause one of said devices to be thrown out of operation when a selected speed has been attained.
48. A machine of the class described having, in combination, a plurality of working devices, actuating mechanism therefor, means under control of the operator for progressively varying the speed at which the devices are driven, and means for throwing one of said devices out of operation when a predetermined speed has been attained and while another device continues in operation, said machine having provision for adjustment to change the speed at which the throwout will occur.
49. A machine of the class described having a plurality of working devices, actuating means therefor, and speed changing means, said machine having one means for suspending the use of one of said devices and for changing the speed at which the devices are operated to a higher speed when the smaller number of devices are used and to a lower speed when the larger number of devices are used.
50. A machine of the class described having, in combination, a pincer; a tacker; actuating mechanism including means for throwing one of said devices out of operation, means for progressively varying the speed of the actuating mechanism; a manually controlled member and connections from the said member to the actuating mechanism, to the speed changing means, and to the throwout means, said machine being arranged to require a noticeable change in operation of said member for each successive control to be established by it.
51. A machine of the class described having, in combination, a pincer; a tacker; actuating mechanism including means for

throwing one of said devices out of operation, speed changing means, a pedal and connections from the pedal to the actuating mechanism, to the speed changing means, and to the throwout means, said machine being arranged to apply an increased load upon the pedal when change is made from low to higher speed and an additional load when the throwout mechanism is actuated.

52. A machine of the class described having, in combination, devices for use in lasting the heel seat and additional devices for use in lasting the toe, actuating mechanism, and a single controlling means to govern the use of said additional devices and to govern the speed of the actuating mechanism according to the devices that are in operation.

53. A machine of the class described having, in combination, actuating mechanism, a pincer, a tacker, a speed changer, and throwout mechanism by which the operation of said pincer is suspended and resumed concurrently with changes in speed.

54. A machine of the class described having, in combination, a pincer, a tacker, actuating mechanism for the pincer and tacker, and a single operating member and connections arranged to first start the machine, then suspend the operation of the pincer, and finally to increase the speed of operation of the tacker.

55. A machine of the class described having two working devices arranged for co-operation in lasting an upper, actuating mechanism therefor, and means to suspend the operation of one of said devices during one or more cycles of the machine and to increase the speed of the other device during such suspension.

56. A machine of the class described having, in combination, lasting devices including a pincer, and a tacker, controlling mechanism including means for varying the speed of the machine, and a single device for throwing the pincer into or out of operation and for changing the speed of operation of the lasting devices at will.

57. A machine of the class described having, in combination, lasting devices including a pincer, a wiper and a tacker, and mechanism including a manually operable member for suspending the action of the pincer and for thereafter increasing or diminishing progressively the speed of operation of the wiper and tacker.

58. In a lasting machine, lasting means including pincers and other devices for working successive parts of an upper over a last, mechanism for varying the speed of the lasting means, and devices for controlling the pincers separately from said other devices and for controlling the speed changing mechanism so arranged that the pincers and the speed changing mechanism may be simultaneously controlled.

59. In a lasting machine, lasting means for working an upper over a last, mechanism for changing the speed of said means, and controlling devices for the lasting means and for the speed changing mechanism arranged so that the character of the operation effected by said lasting means may be changed simultaneously with the change in speed.

60. In a lasting machine, lasting devices having different lasting movements adapted for lasting different parts of a shoe, mechanism for varying the speed of the lasting devices, and controlling means for the movements of the lasting devices and for the speed changing mechanism so arranged that the lasting devices and the speed changing mechanism may be simultaneously controlled.

61. In a lasting machine, lasting pincers and operating means therefor including a cam and a shaft to which the cam is detachably connected, combined with a treadle and a connected lever, a cam and shaft disconnecting member, and a cam connection between the lever and said member arranged to effect stoppage of the gripper cam at a selected point in the depression of the treadle.

62. In a lasting machine, lasting pincers and operating means therefor including a cam and a shaft to which the cam is detachably connected, and a speed changing mechanism, combined with a treadle controlling said mechanism, a shaft and cam disconnecting member, and a cam connection between said treadle and said member arranged to effect stoppage of the gripper cam at a selected point in the movement of the speed changing treadle.

63. In a lasting machine, lasting pincers and operating means therefor including a cam and a driving shaft and having provision for stopping that movement of the pincer normally effected by the cam while the shaft is continued in rotation, and a starting treadle for the machine, combined with a cam member operatively connected with the treadle and formed to effect discontinuance of the pincer movement at a predetermined point in the movement of the starting treadle and while the shaft is continued in rotation.

64. A machine of the class described comprising pincers, operating mechanism for closing the pincers, swinging them laterally to plait, and moving the pincers transversely of the edge of the shoe innersole to overlay the upper on the innersole, and one means for making said operating mechanism inoperative to close the pincers and inoperative to swing the pincers laterally for plaiting the upper.

65. A machine of the class described having, in combination, pincers, a wiping de-

- vice, a shaft, driving cams carried by the shaft and normally connected with the wiper and with the pincers and including means for effecting pincer closing and over-drawing movements, and one means for suspending both the closing and the over-drawing movements of the pincers while the wiping device continues to be operated from said shaft.
- 10 66. A machine of the class described having, in combination, pincers, a wiping device, a shaft, driving cams carried by the shaft and normally connected with the wiper and with the pincers and including means for effecting pincer updrawing, plaiting and overdrawing movements, and one means for suspending the plaiting and the overdrawing movements of the pincers while the wiping device is continued in operation.
- 15 67. A machine of the class described having, in combination, pincers adapted to work on different parts of an upper successively, a tack driving mechanism, means for supplying tacks to said mechanism, means for throwing the pincer out of operation while certain parts of the shoe are being lasted and while continuing to supply tacks from the same means and to insert the tacks, and 20 independent devices for controlling the tack supplying means.
- 25 68. A machine of the class described having, in combination, pincers, a wiper, operating mechanism for the pincers and the wiper, a source of power, and a treadle arranged for manipulation to connect said operating mechanism with the source of power and for further manipulation to render the pincers inoperative while the wiping 30 device continues to run.
- 35 69. A machine of the class described having, in combination, pincers, a wiper, operating mechanism for closing the pincer jaws and moving the pincers to seize and pull the upper and for actuating the wiper to lay the upper into lasted position, a source of power, and a controlling mechanism arranged for manipulation to actuate said operating mechanism to cause the pincers and 40 wiper to do their work and for additional manipulation to cause the operation of one of said working parts to be discontinued while the other continues in action to over-work the upper.
- 45 70. A machine of the class described having, in combination, a pincer, operating mechanism for imparting to the pincer updrawing movements and also plaiting movements, a knee operated means for controlling 50 the plaiting movements and a treadly operated mechanism by which the plaiting movements may be discontinued independently of the knee operated means and while the updraw movements are continued.
- 55 71. A machine of the class described hav- 55 ing, in combination, pincers, operating mechanism therefor, means to control the actuation of the pincers, a driving clutch, one actuator which, by an initial movement, trips the driving clutch of the machine, and operating connections from the actuator to said means through which a further movement of said actuator operates the means that control the actuation of the pincers.
- 60 72. A machine of the class described having, in combination, pincers, a shaft, driving cams carried by the shaft and connected with the pincers to impart a plurality of different movements to the pincers, and connected means for eliminating one of the 65 pincer movements and changing the speed of the shaft.
- 65 73. A machine of the class described having, in combination, pincers, a shaft, driving cams carried by the shaft and connected with the pincers to impart upper plaiting movements to the pincers, tacking mechanism to fasten the upper, and connected means for suspending the operation of the plaiting connections and increasing the 70 speed at which the tacking mechanism is thereafter operated.
- 70 74. A machine of the class described having, in combination, pincers, a shaft, driving cams carried by the shaft and connected with the pincers to impart different movements to the pincers, a tacking mechanism and connected means for changing the speed of operation of the tacking mechanism and effecting a change in the character of the 75 pincer movements.
- 75 75. A machine of the class described having, in combination, operating mechanism, a tacker and coöperating devices to prepare the work for the insertion of a tack, speed 80 changing mechanism, and connected controlling means operating to change the speed and to throw one of said coöperating devices into or out of effective motion according to the change in the speed of the machine.
- 80 76. A machine of the class described comprising pincers, operating mechanism for causing the pincers to seize and to pull a shoe upper, tack driving mechanism, speed changing mechanism, and connections between said speed changing mechanism and the mechanism for operating the pincers whereby when a change in the speed of the tack driving mechanism is 85 made a part of the operating mechanism for the pincers is rendered inoperative to prevent the pincers from pulling the upper while the tack driving mechanism continues to run.
- 85 77. A machine of the class described having, in combination, a tacker, a pincer, a shoe rest, operating mechanism to impart to said pincer and rest relative movements to 90 prepare the upper for the reception of a tack, and connected means for effecting a 95

change in the speed of the operating mechanism and simultaneously eliminating a relative movement of the pincer and rest by which the operation on the upper is modified.

- 5 78. A machine for lasting by operations rapidly repeated on successive portions of a shoe, including pincers and actuating mechanism therefor which produces vibrations
10 of the machine, speed changing mechanism, and connections operating when the higher speed is employed to eliminate a vibration producing motion of the pincer actuating mechanism.
- 15 79. A machine for lasting by operations rapidly repeated on successive portions of a shoe, including pincers and oscillating actuating devices for imparting plaiting movements to the pincers and incidentally causing vibration of the machine, speed chang-

ing mechanism and connections for reducing the vibration of the machine due to said devices when the high speed is used.

80. A machine for lasting by operations rapidly repeated on successive portions of a shoe, including pincers, a cam shaft, and connections to the pincers for imparting plaiting motions to the pincers, speed changing means, and means for causing the motion of said connections to be stopped following a change from a low to a higher speed of the machine.

In testimony whereof we have signed our names to this specification in the presence of two subscribing witnesses.
